Patented Oct. 9, 1917.

FIG. 1.

FIG. 2.

FIG. 3.

UNITED STATES PATENT OFFICE.

CLARENCE J. BROWN, OF CLEVELAND, OHIO, ASSIGNOR OF ONE-HALF TO THOMAS M. CAMPBELL, OF CLEVELAND, OHIO.

TROUSERS HANGER AND PRESSER.

1,242,135.

Specification of Letters Patent. Patented Oct. 9, 1917.

Application filed October 12, 1916. Serial No. 125,329.

To all whom it may concern:

Be it known that I, CLARENCE J. BROWN, a citizen of the United States, resident of Cleveland, county of Cuyahoga, and State 5 of Ohio, have invented new and useful Improvements in Trouser Hangers and Pressers, of which the following is a specification, the principle of the invention being herein explained and the best mode in which I have 10 contemplated applying that principle, so as to distinguish it from other inventions.

My invention relates to clothes hangers and particularly to that class of devices adapted to hold trousers. More particularly, my invention relates to an economically constructed combined trouser retaining and pressing device.

The annexed drawing and the following description set forth certain means exemplifying the spirit of my invention, such disclosed means, however, constituting but one of the various forms in which the same may be used.

In said annexed drawing:—

Figure 1 represents a front elevation of my improved device, showing the pressing member thereof in open position; Fig. 2 represents a side elevation of the parts shown in Fig. 1; and Fig. 3 represents a 30 plan view of the parts as shown in Fig. 1.

In said annexed drawing, 1 represents a back-plate of my improved device, the same being a one-piece member. The front-plate 2 comprises two separate members, 3 an upper retaining member and 4 a lower pressing member. The upper member 3 is connected to the back plate 1 by lugs respectively secured to the inner faces of the plate 1 and the member 3 and relatively pivotally secured together by means of a rod 6 to which the lugs mounted upon plate 1 are secured and upon which the lugs secured to the member 3 are pivotally mounted. Carried upon said rod 6 is a spring 7 so hung 40 as to strongly press with its two ends 7 against the upper front portion of the back-

plate 1 and the upper portion of the member 3, so as to tend to cause the retaining portion 3' of the member 3, to contact tightly with the corresponding section of the back-plate 1. The lower pressing member 4 is connected to the back-plate 1 by the hinges 8. Said lower pressing member 4 is adapted to be locked tightly to the back-plate 1 by the locking devices 9. A rod 10 connected to the upper narrowed portions of the back-plate 1 and the retaining member 3 is utilized for holding the whole device.

It is readily apparent from the accompanying drawing and the foregoing description that the trousers can be tightly hung between the plate 1 and the upper retaining member 3 and the lower parts of the same properly positioned upon the lower portion of the back-plate 1 and then the lower pressing member 4 thrown over and locked tightly by means of the devices 9 against said back-plate, the whole effect being to provide a very efficient and economical hanging and pressing device.

What I claim is:—

In an article of the class described, the combination of a back plate; forwardly projecting lugs secured thereto; a pressing member; means for locking the latter against said back plate; a second member; rearwardly projecting lugs secured to said second member; a rod upon which said last-named lugs are pivotally mounted and to which said first-mentioned lugs are secured, 75 said lugs holding said second member a spaced distance from said back plate, said second member being provided with an offset portion forming a retaining element disposed adjacently to said back plate; and 80 means tending to hold the retaining element of said second member securely against said back plate.

Signed by me, this 6th day of October, 1916.

CLARENCE J. BROWN.
